[73] Assignee: Matsushita Electric Industrial Co.,
Ltd., Osaka, Japan

Primary Examiner—Wallace R. Burke

Assistant Examiner—Joel Sincavage

Attorney, Agent, or Firm—Sughrue, Mion, Zinn,
Macpeak & Seas

[**] Term: 14 Years

CLAIM

[21] Appl. No.: 795,613

The ornamental design for a battery for an IC card, as
shown.

[22] Filed: Nov. 21, 1991

DESCRIPTION

[30] Foreign Application Priority Data
Aug. 9, 1991 [JP] Japan 3-24308
[52] U.S. Cl. D13/103
[58] Field of Search D13/103; 429/96, 98,
429/100, 162, 163

References Cited

FIG. 1 is a front, top and right side perspective view of
a battery for an IC card showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side elevational view thereof; and,
FIG. 7 is a right side elevational view thereof.
